UNITED STATES PATENT OFFICE.

JOHN J. CROSBY, OF DETROIT, MICHIGAN, ASSIGNOR OF ONE-HALF TO PATRICK F. LEAHY, OF DETROIT, MICHIGAN.

BINDING POST.

Application filed January 15, 1927. Serial No. 161,256.

My invention relates to an improved binding post and is intended particularly for use in radio construction wherein a small inexpensive, easily adjustable, spring controlled, positively acting binding post structure is needed, though obviously my improvement is capable of use in other connections wherein the same may be advantageously employed.

10 My invention is designed to provide a binding post which is simple and inexpensive, which is so constructed as to firmly grip and hold a conductor engaged therewith securely in place; which is spring actuated; which is readily accessible for easy adjustment to vary the spring tension; and the moving parts of which are entirely concealed and protected.

20 Other objects and advantages of my improvement will more fully appear from the following description, appended claims, and accompanying drawing wherein a preferred embodiment illustrating my invention is shown.

25 In the drawing:

Fig. 1 is a perspective of a radio cabinet showing my improved invention in use therein.

30 Fig. 2 is a broken away vertical cross-sectional view through my improvement showing a part thereof in elevation.

Fig. 3 is a view similar to that of Fig. 2 except that in Fig. 3 the electric conductor is attached to the binding post.

35 Fig. 4 is a plan of the structure exhibited in Fig. 3.

In the drawing let 10 indicate a base to which my improved binding post is attached. The post is indicated in assembly as 12 and the conductor attached thereto as 14. The post body is here shown as secured to the base by a screw 16. The body structure comprises a portion 18 of enlarged diameter which is internally threaded to receive the screw 16 to secure the binding post in place and a portion 20 of reduced diameter which is externally threaded at 22 and which terminates in a portion 24 of a diameter reduced below that of portion 20. The portion 24 has, in proximity to its end, an aperture 26 adapted to receive an electrical conductor such as 14.

Mounted upon the post is a spring actuated sleeve, indicated in assembly as 28,

which holds the conductor securely in place 55 in the aperture 26 of the post.

The sleeve comprises a pair of telescopic sections—a male section 30 externally threaded to be received within a female section 32, both sections being apertured to be received over the post, the male section being provided with an aperture adapted to be received over the enlarged portion 20 of the post. A nut 34 is threaded on the portion 22 of the post and a spring 36 is mounted upon the 60 post within the sleeve, having one end bearing against the nut 34 and the opposite end against the end of the sleeve to urge the sleeve outwardly to hold the conductor 14 in place in the aperture in the post. Through 65 adjustment of the nut 34 it is readily possible to regulate the tension of the spring 36. The nut 34 forms a stop as shown in Fig. 2 when engaged by the inturned portion of the section 30.

70 My invention is so constructed as to be readily adaptable for use in that it is relatively simple to push back the spring actuated sleeve and insert the conductor in the aperture of the post. Moving parts of the 75 mechanism are completely concealed. The nut within the sleeve serves as an abutment to engage the post as shown in Fig. 1 and is capable of adjustment to regulate the tension on the spring as heretofore described. 80

85 What I claim is:

1. In a binding post, a stationary post member provided with an opening for a conductor, a sleeve comprising a pair of threadedly connected sections slidably mounted 90 upon said stationary post member, a part adjustable upon the post within said sleeve, and a spring within the sleeve engaging said part and acting upon the sleeve to hold the same to securely grip the conductor between the sleeve and the post.

95 2. In a binding post, a stationary post member provided with an aperture at one end to receive a conductor and a threaded portion intermediate its ends, a sleeve slidably mounted upon the stationary post member surrounding the threaded portion thereof, said sleeve comprising a pair of threadedly connected apertured cup sections, a nut 100 adjustably threaded upon the post within the sleeve, a spring within the sleeve surrounding the post engaging said nut and sleeve to act upon the sleeve to hold it out-

wardly toward the end of the post, said nut adapted to serve as a stop to prevent removal of the sleeve from the post.

3. In a binding post, a stationary post member provided with a threaded portion and an end portion of reduced diameter as compared with the threaded portion and having an aperture in proximity to its end, a sleeve slidably mounted upon the post and comprising a pair of cup-like sections, one of which is threaded within the other, one of said cup-like sections provided with an axial aperture receivable over the threaded portion of the post and the other cup-like section provided with an axial aperture re-

ceivable over the apertured end portion of the post, a nut adjustably threaded upon the threaded portion of the post within the sleeve, a spring within the sleeve encircling the post between the nut and the end of the sleeve to hold the sleeve outwardly, a conductor within the aperture of the post held by the sleeve securely therein, said nut being adjustable to vary the tension on said spring and the two sections of said sleeve being relatively adjustable to vary the tension on said spring. 20 25

In testimony whereof, I, JOHN J. CROSBY, sign this specification.

JOHN J. CROSBY.
